UNITED STATES PATENT OFFICE.

JACOB GEORGE SCHWARTZ, OF ROCKINGHAM TOWNSHIP, SCOTT COUNTY, IOWA.

BLOTTING INKSTAND.

Application filed February 2, 1922. Serial No. 533,511.

To all whom it may concern:

Be it known that I, JACOB GEORGE SCHWARTZ, a citizen of the United States, residing at Rockingham Township, in the 5 county of Scott and State of Iowa, have invented a new and useful Blotting Inkstand, of which the following is a specification.

My invention relates to improvements in blotting-inkstands, which combine a tape 10 blotting device with an inkstand; and the objects of my invention are to provide an ever ready means of having a clean blotter, a non-spilling inkstand capable of keeping ink secure against dust and evaporation, in 15 such manner as to combine efficiency with an ample supply of fresh material on hand for the use of the clerical.

I attain these objects by the mechanism 20 illustrated in the accompanying drawings, in which:

Figure 1 is a top plan view of a blotting-inkstand.

Figure 2 is a side elevation disclosing the dipping bowl.

Figure 3 is a plan view of the blotter plate.

Figure 4 is a cross sectional view taken on the line 4—4 of Fig. 1.

Figure 5 is a longitudinal sectional view 30 taken on the line 5—5 of Fig. 1.

Figure 6 is a plan view of one of the sills.

Figures 7 and 8 are respectively side elevation and top plan views of one of the end frames.

Figure 9 is a top plan view of the sill cap disclosing the handle fitting.

Figure 10 is a plan view of the blotter spool.

Similar numerals refer to similar parts 40 throughout the several views.

The general framework of my invention consists of a pair of end frames 2, mounted upon a pair of sills 3, and secured thereto by a sill cap 4, by screw means 4^a, at their 45 tops and by a blotter plate 1 by flange means 1^a and 1^b and screw means 15 at their bottoms, in such manner as to form a housing capable of holding an ink well 8 and blotter roll 13 as shown in Figures 1, 2, 3, 4, and 5.

End frames 2 are preferably constructed of wire but may be constructed of any flexible material capable of being bent and retaining their form, and are constructed, by bending approximately the middle one third 55 of a bar in such way as to form an arc 2^c, of a circle, after which I shape the ends 2^a

of such bar suitable to form the sides and upper part of the box by first bending the end 2^a right-angularly in the direction of the arc 2^c of said circle until said ends 2^a 60 are uprightly parallel to each other after which I further make an S offset 2^b in such parallel ends, said S offset 2^b directioned with the perimeter of the circle, and stationed suitably nearer the extremity of such 65 parallel ends 2^a, and 2^b so formed that the upper end of the S offset 2^b has a larger throat.

I also bend such parallel ends 2^a midway between the S offset 2^b, and the extremity 70 of the arc 2^c the upper part of bent portion 2^c I designate as 29 which bent portion 2^c extends in the direction of the S offset 2^b, and in line with said circle, such bent portion 2^c, being made at an approximate angle 75 of thirty-five degrees from the line of said parallel ends 2^a, thus leaving both parts of the extremity of the said bar adjoining the said offset 2^b, as well, that above: 2^c as that below: 2^c directly in an alignment parallel 80 to each other, yet leaving the upper extremities of those portions designated as 2^c elevated to a common plane and above the extremity of those parts 2^c. Said extremities 2^c, also have right angular offsets 2^d, 85 directioned suitably at a right angle from said circle, in such manner as to form a brace 2^d, said brace 2^d, having at its end a short downwardly extending nib 2^e, suitable for engagement in a vertical hole 3^b found in the 90 top of sill 3 which brace 2^d is laid in a groove 3^a provided in the edge of sill 3 between the end of said sill and said vertical hole 3^b.

It will be observed that it requires two of 95 said end braces 2 and two of said sills 3 in making the proper frame work of my ink stand—and when I attach a pair of braces 2 to the ends of a pair of sills 3, I secure them together by means of cap 5, which cap consists of two strips 4 of suitable material in dimension corresponding to the upper edges of sills 3, which strips 4 are securely rigidly attached unto each other and held in position by clamp 6 also holding 100 a suitable handle 5^b secured thereto by rivets 5^a, and when said strips 4 are placed on top of sills 3 and secured thereto by screws 4^a in holes 3^c they hold the braces 2^d in 105 grooves 3^a, and nibs 2^e in hole 3^b, thus holding said end frames uprightly in vertical 110 position.

Beneath the arc of the circle 2^c of end frames 2, I secure a bottom plate 1, which is a rectangular blank having plural side flanges secured to said frames by protruding side flanges 1^a and 1^b provided on the sides of said plate and which flanges are suitable for bending around the bar of said arc 2^c.

In the center of plate 1 I have provided four holes 1^c suitable for the insertion of screws 15 into holes 9^c provided in the bottom edge of sills 3, which screws 15 connectedly with nibs 2^c and cap 5, hold the frame work together and strengthen the stand.

I have provided the ordinary split spool 14, having an oblong transverse perforation 14^b, disposed through its middle suitable for securing a blotter 13, endwise therein said spool having round ends 14^a suitable for fitting said spools snugly in the larger throat of the S offset 2^b which forms a boxing therefor, so that when spools 14 are placed in the boxing provided therefor in said S offset 2^b and a blotter is passed beneath the plate 1, secured to and wound upon one of said spools with the other end of such blotter secured in the other spool secured in the other boxing provided in the other S offset 2^b such blotter may be wound and re-wound in use as desired.

Sills 3 are formed of any suitable material preferably wood or fibre, of a length and height corresponding to the length and height of ink well and reservoir 8 and are spaced parallel to each other upon arc 2^b, distanced apart corresponding to the width of the ink well and reservoir 8. Said sills 3 are provided with vertical holes 3^c in their top edges to accommodate screw fastening means 4^a of cap 5, and with vertical holes 3^e in their bottom edges to accommodate the fastening means 15 operated through holes 1^c blotter plate 1.

Sills 3 are of uneven thickness having both of their sides rabbeted in such manner as to leave a bench 3^d upon one of their sides which rabbeted sides are intended to face each other and upon which 3^d I mount a suitably proportioned ink well and reservoir 8 beneath cap 5. Said ink and reservoir 8 consist of a square reservoir having a spoon end 8^a and a screw threaded bottle mouth 10^a the bottle mouth being upon the bottom of the reservoir and closed by a screw cap 10 at the end opposite from the spoon end 8^a, the spoon end 8^a being open at the top and provided with screw thread means 9^d for receiving said dip basket 9.

The dip basket 9 is provided with the ordinary plate cover not shown and has a flaring cup portion 9^b, which cup portion 9^b has its bottom open and its lip attached in unit to a downwardly disposed enveloping acorn shaped basket bowl 9^c the lip of which is attached to the lip of cup 9^b in

unit in such manner as to suspend cup 9^b within said basket bowl 9^c, the two being suspended within spoon end 8^a by screw thread means 9^d, in such manner as to let the ink circulate around basket 9^c and enter it at port 9^a when the ink well 8 is mounted right side up.

I provide basket ball 9^e with a port hole 9^a positioned beneath the bottom of cup 9 and beneath the plane of the bottle mouth 10^a and were it not for this port hole 9^a, the said ink pot would when the cap is screwed on bottle mouth 10^a, and dip basket 9 is screwed in, be air tight, but by utilizing the port hole 9^a means, the ink is permitted to escape from the bowl 8^a into basket bowl 9^c.

By reason of the location of port hole 9^a if the ink well be over turned the ink cannot escape from the well, and is kept free from air and dust, no ink may at any time escape from the ink stand excepting what is contained in basket 9^c.

I claim:

1. In a blotting-inkstand, a pair of end braces having arc shaped bottoms, perpendicular ends, boxing means within the upper portion of their ends, other short brace means provided at upwardly disposed ends of the end braces, the last mentioned brace means being provided with vertical nib means suitable for securing the said end braces to the ends of a pair of sill members, which with said end brace members form a part of the frame work of said blotting-inkstand.

2. In a blotting ink-stand, having sill members; said sill members each having one of their sides rabbeted to form a bench suitable for supporting an ink well and reservoir, and having plural hole means right angularly provided in their edges suitable for receiving screw fastening means, said sill members also having angular hole means in one of their edges suitable for receiving the nib fastening means of an end frame and also having groove means provided in the ends of one of their said edges parallel therewith suitable to bed the brace means provided in the elevated portion of an end frame, said sills also having other parallel hole means provided in another of their edges suitable for receiving other screw fastening means.

3. In a blotting-inkstand having sill members, said sill members each having plural hole means provided in one of its edges; a cap consisting of a pair of strip members stationed a suitable distance apart, parallel to each other, and each midway secured upon the end of a clasp member, each of said strip members being provided with plural, vertical hole means stationed suitably near their ends, said holes corresponding to the vertical holes in the edges of the sill members and suitable for engaging screw fas-

tening means suited to connectedly engage in the holes provided in the said strips and the holes provided in the said sills; handle means provided in the engaging recess of 5 said clasp member.

4. In a blotting inkstand composed of an ink well and reservoir member fitted with a frame composed of side brace and sill members, an ink well member having a 10 spoon shaped end, said spoon shaped end being formed in such manner as to permit a dip basket portion thereof to be secured within the perimeter of its brim by screw thread means, the bottom of the spoon end 15 being made lower than the bottom of the reservoir end, the other end of said ink well being box shaped, said box being provided with a bottle mouth outwardly disposed upon its bottom side, said bottle mouth being 20 provided with screw thread means capable of other engagement with other screw thread means of screw cap means provided for closing said bottle mouth; dip basket means having screw thread means 25 outwardly provided around its greater perimeter, capable of engagement with the screw threads of the spoon of the ink reservoir, said dip basket means having an inverted bell-shaped portion attached with its lip in 30 unit, to the larger perimeter of the said dip basket, said bell portion extending with

an open smaller end downwardly into such dip basket; port hole means disposed in line with the bottom of the ink reservoir in the wall of the dip basket, suitable to permit the flow of ink from the spoon shaped 35 end of said reservoir into said dip basket, and to prevent the flow of ink therein when said basket is with the ink well overturned.

5. In a blotting ink stand having a pair 40 of sill members secured upon a pair of end brace members, a blotting plate member, secured unto said end brace members, an ink well and reservoir member mounted between said sill members above said blotting plate 45 member; a pair of blotting spool members supporting a blotter, said spool members being mounted within boxings provided in the ends of said end brace members in such manner as to permit the said spool members 50 to be rolled; a blotter wound upon a spool member said blotter having one of its ends attached to another spool member, and capable of being wound from one spool onto the other; a blotter plate member disposed 55 between said end brace members, and between said spool members in such manner that when said blotter is wound from one spool member to the other, it will cause said blotter to fit snugly against the bottom side 60 of the said blotting plate member.

JACOB GEORGE SCHWARTZ.
